UNITED STATES PATENT OFFICE.

JOHN SCHADE, JR., OF NEW YORK, N. Y., ASSIGNOR TO FAHNESTOCK ELECTRIC COMPANY, OF NEW YORK, N. Y., A CORPORATION OF WEST VIRGINIA.

SPRING FASTENING DEVICE.

1,047,897.

Specification of Letters Patent. Patented Dec. 17, 1912.

Original application filed December 13, 1906, Serial No. 347,577. Divided and this application filed February 28, 1912. Serial No. 680,498.

To all whom it may concern:

Be it known that I, JOHN SCHADE, Jr., a citizen of the United States, and a resident of the borough of Brooklyn, county of 5 Kings, city and State of New York, have invented certain new and useful Improvements in Spring Fastening Devices, of which the following is a specification, accompanied by drawings.

10 This invention relates to spring terminal clips or fastening devices for the terminals of electric conductors, and the objects of the invention are to improve upon the construction of such devices, and enable a spring terminal clip formed out of wire to be firmly secured to a base or support.

This application is a division of my co-pending application, Serial No. 347,577, filed December 13, 1906.

20 Further objects of the invention will hereinafter appear and to all of these ends the invention consists of the fastening device substantially as hereinafter fully described and claimed in this specification and shown 25 in one of its preferred forms in the accompanying drawing, which is a perspective view of the fastening device embodying the invention, secured to a base or support.

My improved fastening device is preferably made from a single piece of resilient material, as for instance, metallic wire, although I am not to be understood as limiting the invention to this particular form of material, for other forms of resilient metal 35 may be found suitable for carrying out the invention. Obviously the device may be made out of a single piece of material or it may be made out of several pieces, if desired, and I am not to be understood as limiting the invention to a fastening device 40 comprised of a single piece of wire.

The fastening device comprises broadly two opposing normally separated members, and a retaining resistant portion of suitable 45 shape projecting toward the opposite member and adapted to co-act therewith to firmly clamp a conductor in defined position when said members are forced into operative relationship. In order to construct 50 two opposing normally separated members, the piece of wire, if the device is made from one piece, is bent upon itself to bring one member opposite the other and the two legs

A may be termed the body member. Both of these legs are adapted to be secured to a 55 base or support I, and in order to accomplish this purpose effectively and in the best manner, the ends of the wire are coiled into rings H, to form a securing eye through which the screw J is passed to hold the device firmly upon the base or support I. The body member is thus fixed stationary upon the base or support, while the opposing member comprising the legs B is adapted to be forced out of its normal position toward 60 the body member, from which it tends to separate under the retractive force of the spring, thus enabling a conductor K to be firmly gripped and clamped in defined position in the member B and in the stationary 70 resistant or retaining portion comprising the bent portions C extending upwardly from the legs A.

The wire as shown is looped on itself to form a spring at D and one end E of the 75 spring member is bent in the reverse direction to the loop D to form with the bend of the loop an angular retaining portion. The other conducting wire L which completes the circuit may be suitably secured in 80 electrical contact with the screw J as by means of the binding nuts O.

While I have shown but one preferred form of the invention, the wire may obviously be bent into different forms without departing from the spirit of the invention, provided the fastening device has rings H forming an eye at its securing end.

I claim and desire to obtain by Letters Patent the following:

1. A fastening device for electrical conductors, formed of bent spring wire and having at its securing end rings forming an eye.
2. A fastening device for electrical conductors, formed of bent spring wire, the ends of the wire being coiled into rings to form a securing eye.

In testimony whereof I have signed this specification in the presence of two sub- 100 scribing witnesses.

JOHN SCHADE, JR.
